APPARATUS FOR FREEING AND REMOVING
HOLLOW CASTINGS FROM FLASKS

Clarence D. Barr, Stephen D. Moxley, and Jacob L. Cooper, Birmingham, Ala., assignors to Sand Spun Patents Corporation, New York, N. Y., a corporation of Delaware

Application January 5, 1932, Serial No. 584,872

8 Claims. (Cl. 22—94)

Our present invention relates to mechanism for removing hollow castings from sand-lined flasks in which they have been cast centrifugally.

In casting hollow metal bodies centrifugally, such for instance as cast iron pipes formed in sand-lined molds or flasks, the castings are often very difficult to remove because the sand lining is usually densely compacted in the flask and the casting, when formed centrifugally, becomes rather firmly bound therein, making it extremely difficult to remove endwise, and this is especially true with cast iron pipes having a protuberance, such as a bead, at the spigot end and a bell at the other end.

It has been proposed to free the castings from the flask by disintegrating the sand lining around the casting by means of a hollow auger, and also by removing the sand lining by means of a jet or jets of fluid under pressure, and while these methods have proven satisfactory, when employed in connection with pipes up to 12" in diameter, some difficulties are presented when an attempt is made to employ them in connection with pipes of larger dimensions, as for instance 14" and over, and of lengths 16' and over.

The objects of the present invention are to provide a novel method of an apparatus for removing hollow metal castings from the sand lined flasks in which they have been cast, and wherein large and heavy flasks and their contained castings may be easily handled with a minimum of labor, exertion and time.

Briefly and generally stated our improved apparatus comprises a support for a flask, which support includes an abutment to prevent endwise movement of the flask in one direction during the extracting operation, a plunger movable within and lengthwise of the flask to push the casting endwise thereof so as to break the "bond" between the sand lining and the flask and cause an end of the casting to be projected through an end of the flask, and a longitudinally movable pulling device having a grapple adapted to grasp the projecting end of the casting and pull it bodily from the flask.

The invention comprises other features of novelty which will be hereinafter pointed out in detail in the following specification and claims.

In the accompanying drawings wherein we have illustrated one embodiment of our invention,

Fig. 1 is a side elevation.

Fig. 2 is an enlarged detail of the grapple for grasping and pulling the pipe from its flask.

Fig. 3 is a transverse view of the flask support taken on the line 3—3, of Fig. 1.

Fig. 4 is a similar view taken on the line 4—4 of Fig. 1.

Fig. 5 is a longitudinal sectional view of the pushing plunger and the flask support with the grapple in open position ready to grasp an end of the casting, and

Fig. 6 is a top plan view of the apparatus shown in Fig. 5.

The apparatus includes a support for the flasks which in the instance shown, comprises a pair of cradles 10, spaced apart a sufficient distance to constitute rests for the flasks 12, to support them horizontally, said cradles being shown as supported upon and secured to I-beams 13, and each having a curved upper face 14, to conform to the radius of the flask or substantially so. Each cradle may also include oppositely arranged vertical uprights 15, bolted to the I-beams 13, and also to I-beams 16, extending at right angles to the I-beams 13. The distance between the uprights of each pair is just sufficient to permit a flask 12, to be supported therebetween. The upper ends of the uprights 15, are beveled outwardly as at 17, to guide the flasks toward the cradle seats as they are lowered by the overhead crane (not shown).

An abutment is arranged in line with the said supports and in the instance shown, consists of a base 18, carrying an annular member 19, of sufficient size to form a stop to prevent endwise movement of the flasks 12, when force is exerted longitudinally thereof, as when a casting is being pushed and pulled therefrom. The annular member is preferably provided with a removable wear-plate 19', bolted thereto, which may be renewed from time to time, or which may be interchanged for a plate of a different size.

In Fig. 5, we have shown the flask 12, in position upon its supports with one end thereof, namely the bell end 12', abutting the abutment member 19'. In said figure the reference character 20 indicates the hollow casting which is shown as a bell and spigot pipe, and 21 indicates the sand lining between the flask and the casting. In this figure the casting is shown as partly pushed from its flask, and through the annular abutment to expose the bell end so that it may be grasped by a grapple and then completely withdrawn from the flask by mechanism to be presently described.

110

The means for breaking the "bond" between the sand lining and the flask and for pushing the casting and the lining endwise of the flask, consists of a plunger 22, having a head 23, of 5 approximately the diameter of the bore of the flask, said plunger being removably mounted upon the extension 22^a of head 22^b, supported from a carriage 24, having wheels 25, traveling upon trackways 26, as more clearly shown in 10 Figs. 4 and 6. The plunger may be withdrawn from the flask by any suitable means. In the present instance I have shown this means as consisting of a weight 27, connected to the carriage 25, by means of cables 28, trained over 15 idlers 29, as more clearly shown in Figs. 1, 5 and 6.

The means for advancing the plunger 22, consists in the instance shown, of a hydraulic or pneumatic power cylinder 30, having one end 20 of its piston 31, directly abutting the outer end of the plunger 22, through a concave convex connection 32, which serves to take care of any difficulties that might arise through misalignment between the pistons 31 and plunger 25 22. The fluid power medium for the cylinder is controlled by a 3-way valve 33, shown conventionally in Fig. 5. Obviously, this valve may be of any improved construction. It will be clear that the return movement of the pistons 30 31, is accomplished by the weight 27, and cables 28, when the valve is positioned to permit escape of the actuating fluid from the power cylinder.

From the foregoing it will be seen that with 35 the mechanism thus far described a hollow casting may be pushed lengthwise of a flask resting horizontally upon its supports with one end engaging the annular abutment member 19, as more clearly shown in Fig. 5. Thus the "bond" 40 between the sand lining and the flask is broken by a "pushing force" directed against one end of the casting to be removed and exerted lengthwise thereof.

In order to completely remove the casting 45 from its flask, we provide a "pulling" means which is brought into operation immediately an end of the casting has been projected through an end of the flask.

Since the art of pulling the casting from its 50 flask also serves to cause the clinging sand to become detached from the casting, some dust is created, and in order to take care of this and to provide means for collecting and for transferring the detached sand to a point where 55 it may be reconditioned for further use, we prefer to pull the casting directly into an enclosure 34, as shown in Fig. 1, with which dust exhaust pipes 35 communicate, said pipes being connected to any suitable exhaust apparatus of the 60 cyclone or other type.

The castings are pulled lengthwise onto transversely arranged rails 36, supported upon the floor of the enclosure and upon which they may be rolled from the enclosure to the cleaning 65 station (not shown). A portion or portions of the floor of the enclosure above a pit or well is covered by a "grating" 37, beneath which are supported hoppers 38, which lead the detached sand to the sand reconditioning apparatus. A 70 stop 39, may be located adjacent one of the rails 36, to properly position the castings upon the rails.

The pulling device for withdrawing the castings comprises, in the instance shown, a grapple 75 as more clearly illustrated in Figs. 1, 2 and 5.

The grapple includes a fixed jaw 40, and a movable jaw 41, both jaws being mounted upon a wheeled carriage 42, which may be caused to travel back and forth upon an I-beam or other trackway 43, extending longitudinally through the enclosure 34. The forward end of the fixed jaw 40, is beveled as at 44, to facilitate its guidance into the end of the hollow casting, and the movable jaw 41, which is pivoted at 45, has a nose 46, adapted to grip the bell end of the casting. The movable jaw also has a shoulder 47, adjacent, but in rear of the nose and so positioned that it will contact with the bell end of the hollow casting when the grapple is brought into grasping relation with the casting and thus automatically bring the two jaws into gripping contact with the said bell end as more clearly shown in Fig. 2. The movable jaw 41, is also provided with a seat 48, in rear of the shoulder 47, with which the free end 49, of a pivoted latch 50, may engage in order to retain the movable jaw into gripping relation with the casting until it is to be released. The latch 50, which is pivoted at 51, is normally urged by gravity into seating relationship with the movable jaw, and is automatically shifted to unlatching position by a stop 52, fixed to the trackway 43, and with which the upper end 53, of the latch engages, all as more clearly shown in Figs. 1 and 2, it being understood that the stop 105 is so positioned that it will actuate the latch to release the movable gripping jaw when the pulling device has withdrawn the casting from its flask and positioned it properly upon the rails 36.

The grapple is actuated by means of a system of cables as more clearly shown in Fig. 1. One cable indicated by the numeral 54, is connected at one end to the fixed jaw 40, of the grapple, and from thence extends through the enclosure 115 34, and is looped around fixed sheaves 55, located adjacent the lower end of a hydraulic cylinder 56, and around movable sheaves 57, mounted at the upper end of a plunger 58, a portion of which plunger is movable in the cylinder as a piston. The other end of the cable is attached to one of said sheaves. Obviously if fluid is caused to enter the lower end of the cylinder 56, the plunger 58, with its sheaves 57, will be elevated thus causing a direct 120 outward pull upon the cable 54, and if the grapple jaws are attached to the casting the latter will be pulled from its flask and deposited upon the rails 36, and the grapple then released by reason of its latch 50, coming into 125 contact with the fixed stop 52.

A second cable 59, is attached at one end to the grapple carriage 42, and then passes over a pulley 60, mounted at one end of the trackway 43, as shown in Fig. 1. From thence the cable 135 59, extends over a series of idlers 61, and then over a sheave 62, mounted upon an overhead beam 63, with portions of the cable looped about sheaves 64, carried by the upper end of the plunger 58, this arrangement being such that the looped portions of the cable will be shortened and lengthened by the upward and downward movements of the plunger 58, as will be obvious. The slack in the cable 59, is taken up by the idler pulley 65, and its associated weight 66, said pulley and weight being suspended in a loop or slack portion 67, of the cable at the point where it is trained over and under the series of idlers 61, as more clearly shown in Fig. 1.

From the arrangement of cables shown and described it will be seen that the grapple and its carriage may be caused to move back and forth upon its trackway 43, by raising and lowering movements of the double acting plunger 58. Obviously as the plunger moves upward it imparts a pulling force upon the cable 54, and at the same time the cable 59, is let out or slackened because of the shortening of the cable 10 loops between the fixed and movable sheaves 62 and 64. When the plunger is lowered just the reverse takes place; the loops in the cable 59 are gradually lengthened, and the grapple carriage with its grapple is then moved into position to grip the casting. The actuating fluid for the cylinder 56, is admitted and discharged at opposite ends thereof, by means of a suitable 15 3-way valve of any preferred construction.

The operation of the apparatus will be clear 20 from the foregoing detailed description and without further explanation, it being apparent that through said operation a novel method is employed for freeing and extracting hollow castings from sand-lined flasks, which consists in 25 first exerting endwise pressure against one end of the casting and the sand lining to break the bond between the lining and the inner wall of the flask and to project one end of the casting through one end of the flask, and thereafter 30 completely removing the casting by a pulling force exerted longitudinally of the casting while maintaining the flask against endwise movement.

By the arrangement shown wherein the head 35 23, is removably mounted upon the extension 22^b of the head 22^a, and wherein the abutment ring 19', is also removable, these parts are interchangeable for corresponding parts of a different size, and the apparatus may thus be readily 40 adapted for use in connection with flasks of different diameters.

While we have shown an apparatus for supporting a single flask only, it is to be understood that in actual operation we prefer to employ 45 two, three or more units of the same construction, said units to be located side by side as indicated in dotted lines in Fig. 3, in order to take care of flasks and castings of different diameters.

50 What we claim is:

1. An apparatus for extracting hollow castings from sand-lined flasks wherein the sand lining is tightly compacted between the outer surface of the casting and the inner wall of the flask, comprising an open support into which a flask may be lowered from above and supported in a substantially horizontal position, an abutment at one end of the support for engagement by an end of the flask to prevent endwise movement thereof in one direction, said abutment having an opening at least as large as the diameter of the casting and thru which the latter may be projected, a plunger located at one end of the support in alinement therewith, means for imparting a short movement to the plunger lengthwise of the flask and operable to engage and project an end only of the casting thru an end of the flask, and a longitudinally movable pulling device having a grapple adapted to engage the projected end of the casting and pull it bodily from the flask to remove it therefrom.
2. An apparatus for extracting hollow castings from sand-lined flasks wherein the sand lining is tightly compacted between the outer surface of the casting and the inner wall of the flask, comprising a fixed support for holding a flask in a substantially horizontal position and said support including cradles having spaced-apart upstanding arms, an abutment at one end of

of the casting and the inner wall of the flask, comprising an open support including oppositely-disposed spaced-apart uprights between which a flask may be lowered and supported in a horizontal position, an abutment at one end 80 of the support for engagement by an end of the flask to prevent endwise movement thereof in one direction, said abutment having an opening larger than the diameter of the casting and thru which the latter may be projected, a fluid-actuated plunger located at one end of the support in alinement therewith, said plunger having a relatively short movement lengthwise of the flask and operable to engage and project an end only of the casting thru an end of the flask, and a longitudinally movable pulling device having a grapple adapted to engage the projected end of the casting and pull it bodily from the flask.

3. An apparatus for extracting hollow castings from sand-lined flasks as defined in claim 1 and including a trackway extending forward from the abutment, a carriage movable upon the trackway and upon which the grapple is mounted, separate cables connected to the grapple and carriage, respectively, and power means for operating the cables for the purpose specified.

4. An apparatus for extracting hollow castings from sand-lined flasks as defined in claim 1, and including a trackway extending forward from the abutment, a carriage movable back and forth upon the trackway and upon which the grapple is mounted, separate cables connected to the carriage and grapple, respectively, and a power plunger common to both cables for operating the latter to pull the grapple and carriage back and forth alternately.

5. An apparatus for extracting hollow castings from sand-lined flasks as defined in claim 1, and including a trackway extending forward from the abutment, a carriage movable back and forth upon the trackway and upon which the grapple is mounted, said grapple having a fixed and a movable jaw to embrace the inner and outer walls of the casting and wherein the movable jaw has a nose adapted to engage the outer wall of a casting and a shoulder positioned to engage an end of the casting to move the nose into gripping position with the outer wall of the casting when the fixed jaw is moved into the open end thereof.

6. An apparatus for extracting hollow castings from sand-lined flasks, comprising an open cradle into which the flask may be lowered and supported in a horizontal position, opposed spaced-apart uprights for holding the flask against lateral movement, an abutment at one end of the support for preventing endwise movement of the flask, said abutment having an opening larger than the diameter of the casting and thru which the latter may be projected, a power plunger at one end of the support having a head mounted for universal movement and adapted to enter the supported flask and push a casting lengthwise thereof, and a carriage upon which the head is mounted.

7. An apparatus for extracting hollow castings from sand-lined flasks wherein the sand lining is tightly compacted between the outer surface of the casting and the inner wall of the flask, comprising a fixed support for holding a flask in a substantially horizontal position and said support including cradles having spaced-apart upstanding arms, an abutment at one end of

the support, said abutment having an opening larger than the diameter of the casting and thru which the latter may be projected, a power plunger at one end of the support, said plunger 5 having an interchangeable head mounted for lateral movement and adapted to enter the flask and engage and push a casting longitudinally thereof, a wheeled carriage upon which the head is mounted, a grapple movable toward and from 10 the other end of the flask and adapted to grasp a casting and pull it bodily therefrom, and a trackway for supporting and guiding the movements of the grapple.

8. In apparatus of the character described 15 for extracting hollow castings from sand-lined flasks, including an open support for holding a flask in a substantially horizontal position during the extracting operation and into which

a flask may be lowered from above, said support comprising spaced-apart cradles each having a curved seat and oppositely-disposed spaced-apart uprights for preventing lateral movement of a supported flask, a vertically-extending abutment 80 at one end of the support for preventing endwise movement of the flask, said abutment having an opening therein larger than the diameter of the casting to be projected from the flask, and a short-stroke power plunger located at 85 that end of the support opposite the abutment, said plunger adapted to enter a supported flask to engage an end of a casting therein to project the opposite end of the casting through the opening in the abutment.
